UNITED STATES PATENT OFFICE.

ULYSSES VICTORIA GARRED, OF LOUISA, KENTUCKY.

MEMORANDUM ATTACHMENT FOR KODAK-ALBUMS.

1,235,434.

Specification of Letters Patent. Patented Mar. 30, 1920.

Application filed February 21, 1919. Serial No. 278,373.

To all whom it may concern:

Be it known that I, ULYSSES V. GARRED, a citizen of the United States, residing at Louisa, in the county of Lawrence and State 5 of Kentucky, have invented a certain new and useful improvement in Memorandum Attachments for Kodak-Albums, of which the following is a specification.

The present invention is a memorandum 10 attachment for kodak, post-card or other picture-albums or scrap-books, or more particularly for the loose leaves of such books.

The main object of the invention is the production of an attachment, as above 15 stated, adapted to receive a record or history of the individual pictures or post cards and which is extremely cheap, neat, compact, giving a graceful appearance and readily attachable to any desired portion of the al- 20 bum.

So far as applicant is aware no satisfactory readily attachable memorandum means has heretofore been provided which is applicable to kodak or post-card album as the 25 picture is inserted or affixed therein.

The important feature of the invention resides in a record tablet or card normally concealed from view under the picture of which it contains a description, the picture 30 being retained in the album or the like in any well known manner. This card having inscribed thereon, either before or after attachment to the album, an autograph, history, description or other interesting information concerning the picture or illustration, is so mounted or fixed in position as 35 will permit it to be drawn into view from under the picture and then replaced after examination.

The invention further resides in the sun- 40 dry details of construction, combination and arrangement of parts hereinafter more fully described and pointed out in the appended claim.

In the drawings which illustrate the preferred embodiments of the invention as at 45 present devised:

Figure 1 shows an album containing photo- 50 graphs with the memorandum attachment applied thereto, the page-mark A disclosing the first embodiment and page-mark B the second embodiment.

Figs. 2 and 3 illustrate the detail construction.

In practice, the memorandum attachment 55 may be applied to the leaves of the book at

the time the pictures are inserted or affixed thereto, or may be applied when the book is being made, as desired.

Referring to the embodiment of the in- 60 vention, a keeper element 1 is provided, preferably from a flat rectangular piece of flexible material, such as paper or cloth, having one surface of its marginal edges coated with an adhesive substance 2 by which it 65 may be affixed to the leaf A of the album and thus leave the center or major portion a thereof unattached to provide a receiv- 70 ing pocket for the card 3. It is to be under- 75 stood, however, that other means than an adhesive may be used to fasten the keeper, if desired.

As shown in the drawing, the keeper is positioned under the picture P suitably dis- 80 posed and maintained on the page by the well-known fanciful corner fasteners C, or the picture may be pasted directly on the page over the keeper 1. The keeper has formed therein adjacent its lower edge 4 and between its side marginal edges, a sub- 85 stantially transverse slit 5 through which the memorandum card 3 is inserted into the receiving pocket a. A finger tab 6 is pro- 90 vided on the lower edges of the card 3 by which the card is reciprocated back and forth from under the picture to its exposed and concealed positions, as shown in Fig. 1, the tab normally projecting through the slit 5 in order that it may be readily grasped. The keepers are to be made of various sizes, 95 but in use should be of smaller size than the pictures with which they are used in order that they will be totally or practically concealed by the pictures. When the keeper is firmly affixed in position, the slit 5 is prefer- 100 ably opposite the lower edge of the picture and its edges will bind or frictionally en- gage with the surface of the card 3 and thus retain the latter in its adjustable positions regardless of the angle to which the book 105 may be moved. It may also be found de- sirable to press the major or center por- 110 tion a of the keeper out of the plane of its securing edges, as shown in Fig. 2 so that the thickness of the card between the keeper and the leaf A will not unduly hinder the proper reciprocating movement of the card and cause the parts to tear. The orna- 115 mental design and color of the keeper 1 and card 3 may, of course, be varied to suit the purpose or use and the desires of the trade.

It is clear from the foregoing that the in-

vention provides a memorandum for pictures applicable to the pages of the album without reducing the picture containing capacity of the page and without interfering with whatever possible arrangement may be desired for pictures on the page. Furthermore, to some persons normally displayed legends or memoranda are objectionable, and it is obvious that this is overcome.

10 Although the preferred embodiment of the invention is fully described, it is to be understood that certain changes in the construction, combination and organization of parts may be made that fall within the scope 15 of the appended claim.

What I claim is:

An attachment for a picture album including a keeper comprising an intermediate portion, lateral edge portions, and a 20 lower edge portion, said intermediate por-

tion being depressed with respect to said lateral and lower edge portions, and said lateral and lower edge portions being attached to a leaf of the album whereby said keeper and leaf are adapted to form a 25 pocket for receiving thereinto and under the lower edge portion a memorandum card, said keeper-intermediate portion having a slit adjacent said lower edge portion thereof for insertion and withdrawal of the memorandum card from said pocket, said slit having its lateral edges adapted to frictionally engage the lateral edges of the memorandum card.

In testimony whereof I affix my signature 30 in the presence of two witnesses:

ULYSSES VICTORIA GARRED.

Witnesses:

L. M. WELLMAN,
J. B. KINSTLER.
